COVER STRUCTURE

Fred E. Hardy, Jr., Ironton, Ohio

Application June 15, 1935, Serial No. 26,838

7 Claims. (Cl. 94—36)

This invention is a hinge for covers of meter casings, man holes, and similar structures.

One of the objects of the invention is to provide a hinge of the character mentioned, so constructed that the parts may not be disengaged unless the cover is moved to an extremely abnormal position. A further object is to provide means to render it impossible to move the cover to such abnormal position while the device is installed in the position which it is normally expected to occupy in use. Another object of the invention is to provide a hinge structure so constructed that the parts may be easily engaged or disengaged, after the installation thereof on the meter casing, man hole, or other similar structure to which it is to be applied. Another object is to provide a hinge structure of the character mentioned, associated with means for locking the cover against pivotal movement.

The invention will be hereinafter fully set forth and particularly pointed out in the claims.

In the accompanying drawing:

Figure 1 is a top plan view of a meter casing, or the like, with the top in closed position;

Figure 2 is an enlarged plan view illustrating the hinge structure;

Figure 3 is a vertical sectional view thereof;

Figure 4 is a detail perspective view of the support member of the hinge; and

Figure 5 is a detail perspective view of the pintle member.

Referring to the drawing, B designates a meter box, man hole or other similar structure preferably of circular cross-section, and constructed of tile, concrete, or other suitable material. Embedded within the casing structure is an anchor member A, which for purposes of illustration is shown of arcuate form in plan view, but not limited to this form, and constructed with two relatively spaced parallel flanges 10, joined by the grid 11, so that it may be embodied in the wall in such manner as to be rigidly held in place.

Extending outwardly from the outer wall 10 of the anchor member A are two support arms 12, laterally spaced with respect to each other, and each having a laterally and inwardly offset bearing portion 13, provided with semi-circular seats 14. Also extending from the outer flange 10, in a normal horizontal position, is a rigid lock member 15, having an outer free end which is turned downwardly on an arc having as its center the center of the arc of the semi-circular seats 14 of the bearings 13, as indicated at 16.

The movable portion of the hinge consists of a pintle 17 formed integrally with supporting arms

18, carried by the cover C, the ends of the pintle extending laterally beyond said arms so as to rest and rotate in the bearing seats 14. The pintle is also provided with one or more enlargements 17^a (two being shown) having peripheral edges 5 concentric with the pintle, and with the overhanging portion 16 of the lock member 15. It will be observed that the enlargements extend around the pintle for something more than 180 degrees, and terminate in shoulders 19 and 20, 10 respectively, which are arranged tangentially with respect to the pintle. The arrangement is such that the enlargements are always in engagement with the lock member 15 and seats 14 during normal rotative movement of the hinge, and may 15 not be disengaged until the cover C has been moved downwardly to a vertical position approximately parallel with the wall of the box B.

In practice, the box B is normally inserted into a suitable hole in the ground, to such a depth 20 that while the cover is in position, it will normally lie flush with the surface of the surrounding ground. The hinge must be connected in operative relation before the box is buried as above suggested. To do this, it is first necessary 25 to place the cover in a horizontal position, as shown in dotted lines at a in Figure 3. This will bring the shoulders 20 of the enlargements parallel with the outer surface of the outside flange 10. Then by pushing the hinge upwardly 30 and rotating the cover downwardly, the pintle may be moved up to a position indicated in dotted lines at b, between the support arms 12 and back and above the plane of the bearings 13. At this time the stop walls 19 of the enlargements will bear against the undersurface of the lock member 15. The cover is then moved toward the depending portion 16 of the rigid lock member until the extremities of the pintle drop into the bearing recesses 14, as indicated in 35 dotted lines c, Figure 3, whereupon by rotating the cover to the right as viewed in said figure and indicated by the dotted line d, the cover may be moved to closed position. Thereafter, while the box is buried, the enlargements 17^a 45 will permit rotation of the cover, because their peripheries are concentric with the curvature of the overhanging portion 16 of the guard and with recesses 14, but it will never be possible to bring the cover to a position corresponding with dotted 50 line position b, because the ground will interfere. Therefore, as long as the box is buried, it will be impossible to detach the cover without breaking or destroying the hinge.

It is preferred to provide the inside flange 55

10 of the support member with a locking lug 21, which is engageable by a button 22 carried by a stud 23, which is rotatively mounted in the cover, said stud having an angular head protruding through the cover, so that it may be engaged by a wrench, or other suitable tool for turning. The button bears upon a cam 24, so that substantial pressure is brought to bear upon it as it engages the lug.

10 The advantages of the invention will be readily apparent to those skilled in the art to which it belongs. For instance, it will be obvious that a very simple and inexpensive hinge is provided, which cannot be disengaged unless the 15 cover may be moved to a position which it is impossible for it to reach while the parts are installed in operative position, so that disengagement of the cover is absolutely prevented unless the hinge is destroyed. A further advantage is 20 that the parts are so constructed and arranged that they may be readily and easily engaged and disengaged before the box is installed in its operative position.

Having thus explained the nature of the invention and described an operative manner of constructing and using the same, although without attempting to set forth all of the forms in which it may be made, or all of the forms of its use, what is claimed is:

30 1. A cover structure of the character described comprising a stationary anchor member having bearing members projecting therefrom, a movable cover member having arms carrying a pintle rotatably mounted in said bearing members, a lock member also extended outwardly from the anchor member at a position between the bearing members and provided with a free end overhanging said pintle, and movable shoulder means carried by the pintle and concentric therewith, said movable shoulder means being so positioned 40 as to rotatively engage the undersurface of the rigid lock member.

2. A cover structure of the character described comprising a stationary support member having bearing members projecting therefrom provided with arcuate seats, a movable cover member having arms carrying a pintle rotatably mounted in said seats, a rigid lock member having a down-turned arcuate portion overhanging said pintle, and radial enlargements on said pintle concentric with and rotatively engaging the arcuate portion of said rigid lock.

3. A cover structure of the character described comprising a stationary support member having bearing members projecting therefrom provided with arcuate bearing surfaces, a movable cover member carrying a pintle which is rotatively mounted in said bearing members, a rigid lock member having an arcuate down-turned portion overhanging said pintle and concentric enlargements carried by said pintle, said enlargements being also concentric with and rotatively engaging the undersurface of the down-turned arcuate portion of the rigid lock member, said en-

largements having shoulders arranged tangentially with respect to said pintle.

4. A cover structure of the character described comprising a stationary support member having support arms extended therefrom, said arms being provided with laterally and inwardly extended bearing portions, a movable cover member carrying a pintle rotatably mounted in said bearing portions, a rigid lock member projecting from the support member and having an arcuate 10 down-turned portion overhanging said pintle and concentric therewith, and arcuate enlargements carried by said bearing portions at positions spaced from the ends thereof and normally located beneath and rotatively engaging the 15 arcuate down-turned portion of said rigid lock member.

5. A cover structure of the character described comprising an arcuate anchor member having relatively spaced inner and outer flanges, support arms projecting outwardly from the outside flange of said anchor member, said arms having bearings at their ends, a movable cover member carrying a pintle rotatably mounted in said bearings, a rigid lock member projecting from 25 said outside flange and having an arcuate portion overhanging said pintle and concentric therewith, and arcuate shoulder means carried by the pintle and rotatively engaging the under- 30 side of the overhanging portion of said rigid lock member.

6. A cover structure of the character described comprising a stationary support member provided with an inner locking lug and with outwardly projecting bearing arms, a movable cover 35 member having arms carrying a pintle rotatably mounted in said arms, a rigid lock member having an arcuate portion concentric with said bearing arms and overhanging the same, arcuate shoulder members carried by said pintle and 40 concentric therewith and also concentric with and rotatively engaging the arcuate portion of the rigid lock member, and means carried by said movable member for engaging said lug.

7. A cover structure of the character described comprising an arcuate member having inner and outer arcuate flanges arranged in parallel relation, the inner flange having a locking lug projecting therefrom, the outer flange having bearing members projecting outwardly therefrom, a rigid lock member also projecting outwardly from said outer flange, a movable cover member having a pintle rotatively engaging said bearing members, arcuate enlargements carried by said pintle and concentric therewith and also with 55 said rigid lock member, said enlargements normally having rotative engagement with the underside of said rigid lock member, a stud rotatively mounted in said movable cover member and carrying a button engageable with said lug, 60 and means for creating a locking tension on said button as it is moved into engagement with said lug.
